UNITED STATES PATENT OFFICE

CHARLES HEUZE, OF AUVELAIS, BELGIUM, ASSIGNOR, BY MESNE ASSIGNMENTS, TO
THE AMERICAN BICHEROUX COMPANY, A CORPORATION OF DELAWARE

PROCESS AND APPARATUS FOR THE MANUFACTURE OF GLASS

Application filed June 19, 1928, Serial No. 286,684, and in Belgium March 3, 1928.

The invention relates to annealing glass sheets or plates produced by intermittently acting forming machines.

It is known that in the method of forming it is advantageous to roll at relatively high speed. However, high speed of formation greatly complicates the subsequent treatment of the sheets during annealing, as the annealing is only a function of time and decreasing temperatures and as if, in intermittent manufacture, the sheets or plates, particularly when of great thickness, are carried along at speed of formation during annealing, the annealing apparatus must be of excessive length.

On the other hand, modification of the speed of the sheets or plates in the annealing apparatus itself, is, unless special provisions are made therefor, attended with a loss of useful space in the lehr and the apparatus for driving the conveyer rollers is complex and delicate, thus increasing the cost of installation and maintenance.

This invention is designed to overcome the defects set forth and relates to a process and apparatus wherein sheets or plates are intermittently formed at high speed and annealed while moved at a reduced speed, wherein the annealing apparatus may retain its normal dimensions and be completely utilized over its entire extent. To accomplish this an intermediate period is provided between the high speed rolling and the low speed annealing, during which intermediate period the rate of movement or advance of the sheets or plates is modified. In other words, a sheet or plate formed at high speed is received in a waiting position while the next sheet or plate is rolled and the previously rolled sheet or plate is being passed into the annealing apparatus at reduced speed.

The invention also consists in utilizing the intermediate or waiting period as a pre-annealing period for the sheets or plates, during which period they are carried into a position for introduction into the annealing apparatus. It also contemplates, during this same period, in maintaining the sheets or plates in constant movement, such as to produce practically complete flattening by the time

they are introduced into the annealing apparatus.

In addition to the process the invention also comprises an apparatus for carrying out said process.

In its simplest form, assuming the arrangement of a rolling machine and an annealing apparatus provided with a system of conveyer rollers, this process may be carried out by means of two movable sheet receiving tables, each having a bed made up of conveyer rollers, and presented successively before a rolling machine which is located alternately at each side of the longitudinal axis of the annealing apparatus, one table being in position in front of the machine to receive the sheet or plate to be rolled or in the course of rolling, and the other table being in position in front of the annealing apparatus for introducing the precedingly rolled sheet thereto. The table in front of the rolling machine has its rollers driven so that their peripheral speed corresponds to or is slightly greater than the rolling speed, and as soon as the sheet or plate has passed entirely from the rolling machine and is resting on the table, the rollers of the latter are given an alternating rotary movement so as to maintain the sheet or plate in constant movement, until the table is carried opposite the entrance to the annealing apparatus, after which the rollers of said table are driven at a peripheral speed equal to that of the supporting rollers of the annealing apparatus, for introducing the sheet or plate into this latter.

As the sheet or plate may cool down considerably during this intermediate period, means are preferably provided such as shields or hoods adapted to be folded down as desired in the vicinity of the sheet or plate so as to moderate and regulate its cooling.

The invention is described in detail hereinafter with reference to the accompanying drawings, wherein:

Fig. 1 is a diagrammatic plan view of an assembled plant for rolling and annealing glass sheets or plates according to the invention.

Fig. 2 is a diagrammatic section on line A—B of Fig. 1.

Fig. 3 is a plan view of a modification form of my invention.

Referring to Figs. 1 and 2, assuming that in accordance with the invention it is desired to manufacture glass sheets or plates by the intermittent method, there is provided a rolling machine A, for example of the Bicheroux type, comprising a pair of sheet forming rolls 1 and 2 and a delivery apron 4.

10 This rolling machine A is movable on tracks 3 so as to assume one of the positions I or II, at each side of the longitudinal axis of the lehr 5, only a portion of which is shown.

15 Two carriages or tables 6 and 7 are mounted on wheels traveling on tracks 8 and 9 parallel with those 3 of the rolling machine, so as to come into the two rolling positions.

20 The beds of the carriages are formed by rollers 6^a, 7^a driven by suitable drive mechanisms capable of communicating thereto a continuous rotary movement at a peripheral speed at least equal to or slightly greater than the feed of the rolling machine, an alternate rotary movement, and finally a continuous rotary movement at a peripheral speed corresponding to that of the rollers 5^a of the annealing apparatus, which speed is less than the speed of sheet formation. The rollers 6^a, 7^a are substantially parallel with the forming 25 rollers 1 and 2 so that the axis of each train formed by the rollers 6^a, 7^a is, when such train is opposite the forming machine, in line with the axis of the forming machine.

30 In order to assure these drives each carriage may be provided with one or more motors, such as a reversible electric motor 10 which, through a reducing gear train 10^a, and a clutch device 11, acts on the longitudinal shaft 12 connected by bevel gears or pinions 35 13 with the shafts of the rollers 6^a, 7^a to rotate the latter continuously at either one of two speeds, and an electric motor 14 which, through a crank device and a clutch 15, communicates to said shaft 12 an alternate rotation, by which the rollers 6^a and 7^a will be alternately rotated in reverse directions.

35 The rollers 6^a and 7^a may also be driven, if desired, by the drive mechanism which drives the forming rolls 1 and 2 for the period during 40 which the rollers 6^a and 7^a rotate at high speed, and by the drive mechanism which drives the rollers 5^a of the annealing apparatus during which the rollers 6^a and 7^a are driven at a reduced speed.

45 A drive system of this kind is shown diagrammatically at the lower part of Fig. 1, comprising clutches 16 and 17 for table 6 and 18-19 for table 7, whereby the drive for the rollers 6^a and 7^a may be taken from the drive 50 for the rollers 5^a.

55 If desired, use is made of a mixed or composite system comprising the drive electric motor 14' and clutch system 16-17 to assure synchronous rotation.

60 65 In addition, carriages 6 and 7 are provided

with means to carry them from one or the other rolling position I and II to the introducing position III, said means for instance comprising for each carriage an electric motor 20 coupled to the supporting wheels for that carriage.

Finally, for retarding and if necessary regulating the cooling of the sheets or plates on the roller tables, there may be provided, as shown on Fig. 2, shields or hoods 21 mounted 75 on the carriages, these being adapted to be raised and lowered as desired, for example by means of a rod 22 shown in broken lines on said figure.

80 The arrangement being as described, assuming that during the course of manufacture, the elements occupy the position as shown on Fig. 1, a sheet of glass is rolled on the forming machine A, and the rollers 6^a of carriage 6 are rotated at the speed of 85 sheet formation, the result being that the sheet or plate advances at high speed on the roller train of carriage 6.

90 As soon as the sheet or plate is completely deposited on this roller train, the high speed drive for the rollers 6^a is uncoupled and the alternating and reciprocating drive from motor 14 is so connected that the sheet or plate is moved back and forth along the carriage, the result of which is to cause the disappearance of the slight undulations formed in the sheet or plate at their arrival on the rollers.

95 While a sheet is being thus fed to and handled by table 6 at position I, the previously formed sheet which is on table 7 is fed into the lehr 5 by driving the rollers 7^a of that table at a reduced peripheral speed equal to that of the rollers 5^a of the lehr.

100 As soon as the sheet or plate is completely fed into the lehr from the carriage 7, carriage 7 is moved to position II, the rolling machine A is moved into the same position II and the carriage or table 6 is moved opposite the entrance to the lehr. This being done, the rollers of carriage 6 are driven at reduced speed 105 to introduce the sheet or plate into apparatus 5.

110 A sheet is now delivered to carriage 7 while in position II, and the operations above 115 described repeated on carriage 7.

115 If necessary, while the sheets or plates are on carriages 6 and 7 awaiting introduction into the annealing apparatus, the shields or hoods may be manipulated so as to fold them down in the vicinity of the sheets or plates and thus surrounding the latter by a partially or completely closed casing, for the purpose of slowing down their cooling.

120 The apron 4 which is inclined may be of such length that the sheet may be more or less cooled before it reaches the roller bed. This prevents the ends of the sheet sagging between the rolls of the bed as it is reciprocated thereon.

Fig. 3 shows the same apparatus as precedingly described, but in a radiating arrangement, the rolling machine A again occupying positions I and II and the roller tables or carriages moving in an arc into these positions and to another position for introduction into lehr 5, arranged preferably at the bi-section of the angle of the two rolling positions. In this construction the conversion of the high speed operation into reduced speed operation and the feeding into the lehr is effected as in the first case.

Since, on the one hand, these tables or carriages provided with rollers, to a certain degree perform the function of a pre-annealing chamber, the first rollers of the annealing apparatus are in contact only with sheets or plates which have appreciably cooled, and thus less liable to deformation and, as on the other hand, the tables or carriages by retaining the sheets or plates thereon during a part of their cooling period, the dimensions of the annealing apparatus may be reduced proportionately. These tables also permit of compensating for the slight differences of time in the rolling operations, and assuring complete utilization of the annealing apparatus throughout its entire extent.

Finally, the use of these tables permits, without mechanical complications, the flattening or smoothing of the sheets or plates when these are undulating as a result of the forming process. Such undulations when produced are removed by the reversal of the sheets on the table and much better results are obtained than by continuous movement of the annealing apparatus.

It is understood that the invention may be modified without departing from the scope thereof.

Having thus described my invention what I claim as new and desire to secure by Letters Patent, is:

1. The hereinbefore described process for the manufacture and annealing of glass sheets, comprising a forming step accomplished at high speed, an annealing step during which the sheet moves at a reduced speed, and an intermediate step during which the sheet is given an alternate fore and aft movement.

2. The hereinbefore described process of manufacturing and annealing glass sheets, comprising forming a sheet at high speed and delivering the same as formed to a train of rollers, the axis of the train being in line with the axis of the forming machine and the peripheral speed of the rollers being the same as the speed of sheet formation, moving the sheet while on the train transversely out of alignment with the forming machine instrumentalities and in alignment with a lehr, and feeding the sheet off the train of rollers and towards a lehr at a reduced speed by

continuously rotating the rollers of the train at a reduced speed.

3. The hereinbefore described process of manufacturing and annealing glass sheets comprising forming a sheet at high speed and delivering the same as formed to a train of rollers, the axis of the train being in line with the axis of the forming machine and the rollers being driven at a peripheral speed the same as the speed of formation, moving the sheet when on the train back and forth thereon by alternate rotation of the rollers of the train and transversely out of alignment with the forming machine and into alignment with a lehr by a bodily movement of the train, and feeding the sheet off the train of rollers towards the lehr by continuously rotating the rollers of the train at a reduced speed.

4. In an apparatus for the intermittent manufacture of glass sheets, the combination of a sheet forming machine, of a roller bed receiving the sheets as formed, means for successively continually rotating certain of the rollers of the said bed at a high speed, for imparting alternate reciprocating rotation to the said rollers and for rotating them continually at a low speed, a conveyer having a low speed of movement to which the sheets are delivered from the roller bed, and means for controlling the cooling of the sheets.

5. In an apparatus for the intermittent manufacture of glass sheets, the combination of a sheet forming machine, means to move the same transversely of its line of feed into two forming positions, a lehr provided with means for feeding the sheets therethrough at a speed less than the speed of sheet formation, a plurality of carriages, means for moving each carriage from one of the sheet forming positions into alignment with the lehr, a roller bed carried by each carriage, and means for driving the rollers of the said beds at speed of sheet formation and at the speed of lehr feed.

6. In an apparatus for the intermittent manufacture of glass sheets the combination of a sheet forming machine, means to move the same transversely of its line of feed into two rolling positions, a lehr provided with means for feeding the sheets therethrough at a speed less than that of the speed of sheet formation, a plurality of carriages, means for moving each carriage from one of the sheet forming positions into alignment with the lehr, a roller bed carried by each carriage, and means for continually rotating the rollers of the said beds at speed of sheet formation and at the speed of lehr, and for alternately rotating the said rollers at will.

7. The hereinbefore described method of transporting glass sheets from a forming machine to a lehr, which comprises carrying the sheets after they are fully formed on a series of rollers and imparting to such sheets a

back and forth movement by a reverse rotation of the rollers.

8. The hereinbefore described method of handling and flattening sheet glass during a portion of its cooling period and after it has been formed, which comprises receiving the formed sheet from a forming machine on a roller bed at the speed of sheet formation, and while the sheet is free of the forming machine, giving the sheet a back and forth movement by alternate rotation of the rollers.

9. The combination with a glass sheet forming mechanism including a forming pass, of a bed to receive the sheet when and as formed, and comprising a series of glass supporting rollers, means for driving the rollers at the speed of sheet formation to take the sheet from the forming pass, for subsequently imparting alternate reciprocations thereto, and for then continuing the forward motion of the sheet in the direction as it was taken from the machine, means for controlling the heat losses of the sheet while reciprocated by the last-named motion of the rollers.
